UNITED STATES PATENT OFFICE.

JAMES E. MONTGOMERY AND WILLIAM C. HATCHER, OF NORBORNE, MO.

GAGE.

SPECIFICATION forming part of Letters Patent No. 340,592, dated April 27, 1886.

Application filed February 1, 1886. Serial No. 190,479. (No model.)

To all whom it may concern:

Be it known that we, JAMES E. MONTGOMERY and WILLIAM C. HATCHER, citizens of the United States, residing at Norborne, in 5 the county of Carroll and State of Missouri, have invented certain new and useful Improvements in Weather-Boarding Gages; and we do declare the following to be a full, clear, and exact description of the invention, such as will 10 enable others skilled in the art to which it app pertains to make and use the same, reference being had to the accompanying drawings, and to the letters and figures of reference marked thereon, which form a part of this specifica- 15

Our invention is a gage for carpenters' use, and is designed especially for use in building frame houses.

It consists in the novel construction and 20 combination of the parts, as hereinafter fully described, and pointed out in the claims.

In the accompanying drawings, Figure 1 is a side elevation of our device, showing it as applied to the side of a building, which is 25 shown in section. Fig. 2 is a front elevation, and Fig. 3 is a detail side view, of our device, showing it folded for packing or transportation.

Referring to the drawings, A designates the 30 main bar of our device. It consists of a flat iron or steel bar having its ends *a a'* bent at right angles, as shown, for the purposes pres- 35ently set forth. The edges of this main bar are made perfectly straight, and a measure, *A'*, is marked along one of them, as shown in Fig. 2. The main bar is also provided with a slot or groove, *A²*, as shown. A sup- 40 plemental bar, B, is adjustably pivotally secured to the main bar by means of a screw, C, and a thumb-nut C'. The screw C is passed through a screw-hole in the upper end of the main bar and a slot, *B'*, in the lower end of the sup- 45 plemental bar, and the thumb-nut C' is passed over the end of the screw and turned up against the bar B, as shown in Fig. 1. This supplemental bar B has its upper end, *B²*, turned at right angles and provided with a sharpened edge, as most clearly shown in Fig. 1. The lower end of the bar B is provided 50 with a lug or boss, *b*, which works in the slot or groove *A²* in the main bar A.

The manner of using our device will be readily understood. The lowest two boards are secured in position on the building and properly spaced. The gage is then applied 55 by placing the main bar against the weather-boarding, as shown in Fig. 1. The supplemental bar is then adjusted upon the main bar until the distance between the end *a* of the main bar and the end *B²* of the supplemental 60 bar is equal to the distance between the lower edges of the overlapping boards.

The adjustment of the supplemental bar is readily effected by reason of the slot *B'* and thumb-nut C' turning on the screw C, passed 65 through the said slot, as will be readily un- 70 derstood. The lug or boss *b*, working in the groove or slot *A²*, prevents the supplemental bar turning upon the screw C as a pivot in case the thumb-nut fails to secure it, and we 75 thus doubly provide for holding the sup- 80 plemental bar in the position to which it may be adjusted.

After the adjustment of the supplemental bar has been effected the device is applied, as 75 shown in Fig. 1, with the upper bent end, *a*, of the main bar resting against the lower edge of the board last secured in position. The sharpened or pointed bent end *B²* of the supplemental bar is then forced into the be- 80 fore-mentioned last-laid board, making a cut or puncture therein, as will be readily un- 85 derstood. Tacks or small nails are then driven in the line of these cuts or punctures, with a portion projecting, upon which the next board 90 rests until properly secured in position in the ordinary manner. This operation is repeated until the entire weather-boarding is secured 95 in position.

When it is desired to fit the ends of the 90 boards to a corner of the house or to a win- 95 dow or door frame, the gage is placed in posi- 100 tion, as shown in Fig. 2, with the upper hook, *a*, of the main bar resting upon the upper edge of the board last placed in position, and with both hooks *a a'* resting against the post or frame D. A knife, pencil, or any conven- 105 ient device is then drawn along the edge of the main bar across the board, thereby accu- 110 rately indicating how much of the board is to be cut off.

When the device is not in use, it can be

folded, so as to be conveniently carried by loosening the thumb-nut C sufficiently to allow the supplemental bar to be drawn away from the main bar, so as to disengage the lug 5 b from the groove A². The supplemental bar is then given one-half of a complete revolution and the thumb-nut tightened, when the several parts will have the relative positions shown in Fig. 3, and the device will be in 10 convenient form to carry.

Having thus described our invention, what we claim, and desire to secure by Letters Patent, is—

1. The combination of the main bar having 15 a groove or slot through a portion of its length, the supplemental bar provided on its lower end with a lug which works in the groove or slot in the main bar, and on its upper end with a marker or pointer, and a screw 20 and thumb-nut for securing the two bars together, whereby they may be adjusted longitudinally, the one over the other, and folded, substantially as set forth.

2. The herein shown and described weather-boarding gage, consisting of a main bar 25 having its end bent at right angles and provided with a slot or groove through a portion of its length, a supplemental bar having its upper end bent at a right angle and sharpened, and provided with a slot near its lower 30 end, and having a lug or boss at its lower end, which works in the groove or slot in the main bar, and a screw passed through a hole in the main bar and the slot in the supplemental bar, and provided with a thumb-nut, substantially 35 as specified.

In testimony whereof we affix our signatures in presence of two witnesses.

JAMES E. MONTGOMERY.
WILLIAM C. HATCHER.
